UNITED STATES PATENT OFFICE.

FRANK M. ARCHER, OF NEW YORK, N. Y., ASSIGNOR TO SIEGFRIED SILBERBERG, OF SAME PLACE.

ELECTRICAL BEDBUG-EXTERMINATOR.

SPECIFICATION forming part of Letters Patent No. 616,049, dated December 18, 1898.

Application filed February 7, 1898. Serial No. 669,334. (No model.)

To all whom it may concern:

Be it known that I, FRANK M. ARCHER, a citizen of the United States, residing at New York city, in the county of Kings and State 5 of New York, have invented certain new and useful Improvements in Electrical Bedbug-Exterminators, of which the following is a full, clear, and exact description.

This invention relates to bedbug-exterminators; and it consists of electrical devices applied to bedsteads in such a manner that currents of electricity will be sent through the bodies of the bugs, which will either kill them or startle them, so that they will leave the bedstead. The electrical devices used consist of a battery, induction-coil, a switch, and a number of circuits leading to various locations on the bedstead, where are placed suitable circuit-terminals, arranged so that the bugs in 20 moving about will close the circuit through their own bodies.

In the accompanying drawings, which illustrate my invention, Figure 1 shows a portion of a bedstead with the electrical devices attached to the inside of the side pieces of the bed. Fig. 2 shows one arrangement of contact-terminals applied to the surface of the bedstead. Fig. 3 is a perspective view of a joint in the bedstead, showing the contiguous 25 edges of the joint fitted with contact-terminals; and Fig. 4 is a diagram of the circuits.

Let A represent the bedstead. I propose to fit it with a battery b, an induction-coil c, commonly known as a "medical" coil, and a switch s, by which the apparatus may be put 30 into and out of operation. These devices are preferably attached to some portion of the bedstead. On metal bedsteads they can easily be secured on the inside of the angle-iron of which the side pieces are made; but on wooden bedsteads they may be placed in any location where they will not be seen. At 35 proper locations on the bedstead, preferably such locations as are inhabited to the greatest extent by the bedbugs, such as at the joints and angles, I place pairs of metallic contacts, insulated from each other, but so close together that an insect in passing from one to the other must necessarily close the circuit 40 between the contacts. Such a pair of con-

tacts I have shown in Fig. 2. Here they consist of two metallic rings c c', surrounding a cylindrical portion of the bedstead, such as a leg, and insulated by a hard-rubber or fiber bushing d. The positive and negative wires 45 from the battery and coil are connected, respectively, to these rings. The space c' between the rings is such that a bug in crossing from one to the other must close the circuit through its own body, and thus receive a current of electricity. If these rings are placed on a leg of the bedstead, an insect in climbing up will when it receives the shock more than likely change its mind and return in the direction whence it came. Another location 55 where the contacts would be particularly efficient is at the joints between the side pieces and the head and foot boards. A perspective of such a joint is shown in Fig. 3. A pair of insulated contact-strips e and e' is placed along 60 each of the contiguous edges of the joint and surrounding the joint on all sides. The polarities of these strips are so arranged that a positive and negative strip will be next to the respective edges, so that the insect in crossing a pair or the adjacent members of the two pairs will necessarily receive a current, which will either terminate its career at once or make it seek other locations. In like manner contact-strips in pairs, constituting the 65 terminals of the circuit, may be located at various places on the bedstead or on the bed-springs, which will so harass the bugs as to cause them to shun the bed entirely.

Obviously the apparatus need not be in operation all the time. It may be in operation during the day and shut off at night by opening the switch, and after the insects have been exterminated from the bed it need be used only at long intervals. The circuits 70 are shown in Fig. 4, wherein the contact-terminals are placed in multiple with each other; but it is obvious that other circuits may be used and that the battery, coil, and switch, one or all, may be placed in some other location than on the bedstead.

Having thus described my invention, I claim—

1. The combination with a bedstead, of one or more pairs of electrical contacts consist-

ing of strips surrounding the bars or framework of the bedstead and insulated from each other, whereby an insect, in traversing the bar or frame in the direction of its length, 5 must necessarily close the circuit between the contacts, and a source of electricity connected with said contacts, substantially as described.

2. The combination with a bedstead, of an 10 electric battery and an induction-coil attached to the inner side of the side bars thereof, an electric circuit leading therefrom to various locations on the bedstead, and insulated pairs 15 of electric contacts secured to the bedstead

at various points and connected in said circuit, as and for the purpose set forth.

3. In a bedstead, a joint whose abutting faces are provided with electrical circuit-terminals, in combination with a source of electricity and a circuit leading therefrom to said 20 terminals, substantially as described.

In witness whereof I subscribe my signature in presence of two witnesses.

FRANK M. ARCHER.
